UNITED STATES PATENT OFFICE.

WENSEL MORAVA, OF CHICAGO, ILLINOIS.

ELECTRIC RIVETER.

1,195,928.

Specification of Letters Patent. Patented Aug. 22, 1916.

Application filed November 27, 1914. Serial No. 874,148.

To all whom it may concern:

Be it known that I, WENSEL MORAVA, a citizen of the United States, residing at Chicago, in the county of Cook and State 5 of Illinois, have invented a certain new and useful Improvement in Electric Riveters, of which the following is a specification.

My invention relates to improvements in riveting machines.

10 It has for one object to provide a new and improved form of portable riveting machine which may be driven by an electric motor.

15 My invention is illustrated more or less diagrammatically in one form in the accompanying drawings, wherein—

Figure 1 is a side elevation in part section. Fig. 2 is a detail in part section on an enlarged scale of the upper portion of Fig. 20 1. Fig. 3 is an end elevation in part section of the controlling mechanism shown on the upper part of Fig. 1. Fig. 4 is a section along the line 3—3 of Fig. 3. Fig. 5 is a section along the line 5—5 of Fig. 4. Fig. 25 6 is a wiring diagram.

Like parts are indicated by like letters in all of the figures.

A is the ordinary type of jaw frame having a fixed rivet head die A¹ mounted on 20 the lower arm member.

A² is a bearing and guide sleeve integral with and mounted on the upper arm member.

35 A³ is an extension or bracket projecting rearwardly from the upper arm member.

A⁴ are bosses whereby the riveter may be pivotally suspended by any suitable means not here shown.

40 A⁵ is a dolly bar slidably mounted in the bearing sleeve A² and carrying on its lower end a removable rivet head die A⁶.

A⁷, A⁷, are links pivoted at one end on opposed sides of the lower end of the sleeve A² and in pivotal engagement at the other 45 end with a central link A⁸ which is pivoted at its lower end on the dolly bar A⁵.

B, B¹ are brackets mounted one on the upper jaw arm, the other on the part A³.

50 B² is a crosshead guide rigidly supported at either end by the brackets B, B¹.

B³ is a crosshead slidable along the crosshead guide B², and held in position thereon by a cap B⁴.

55 B⁵, B⁵, are links pivotally mounted each at one side on opposed sides of the crosshead B³ and each at the other end on the

pin B⁶ upon which the links A⁷, A⁸ are also pivoted.

C is a bracket mounted upon the part A³, and having a thrust-bearing C¹ to engage the thrust collars C² on the rotary shaft C³. This rotary shaft C³ is rotatable in a bearing C⁴ on the bracket B⁴, and terminates in a screw C⁵ which is threaded in the cross-head B³.

60 C⁶ is a housing mounted on and projecting from the crosshead B³ to inclose the screw C⁵ when the crosshead is in its retracted position.

C⁷ is a thrust collar on the shaft C³ bearing against the end of the bearing C⁴.

70 D is a clutch disk or spider provided with the hub D¹ free to rotate about the shaft C³ but held against longitudinal movement therealong by the collar D². D³ is a conical clutch ring on the periphery of the spider D.

75 D⁴ is a clutch spider provided with a hub D⁶ slidable along the shaft C³ but held against rotation thereabout by a key D⁷ which passes through a slot D⁸ therein and attached at either end to bosses D⁹.

80 D¹⁰ is a male clutch cone mounted on the spider D⁴ in opposition to the female clutch ring D³.

E is an internal gear ring attached to and 85 projecting from the rear of the ring D³ or the periphery of the wheel D. In mesh with it is a pinion E¹ driven by the electric motor E² and fly wheel E³.

E⁴ is a hub slidably and rotatably mounted 90 on the shaft C³ and limited in its backward movement by the hub D¹.

E⁵ is a clutch spider projecting from the hub E⁴ having a gear E⁶ about the periphery thereof in mesh with the pinion E¹ and 95 a female conical clutch member E⁷ in opposition to the male cone clutch member E⁸.

E⁹ is a key slidable in the slot E¹⁰ in the shaft C³ attached at either end to lugs E¹¹ on the hub E¹² which is slidably mounted on 100 the shaft C³ and carries the member E⁸.

The rear end of the shaft C³ is centrally apertured as indicated at H, and in this central aperture is slidably mounted a control shaft H¹ through which pass the keys 105 E⁹ and D⁷.

H² is a screw threaded sleeve attached to the bearing C¹. Through the center of this sleeve projects the end of the shaft H¹.

H³ is a nut rotatably mounted on the 110 shaft H¹ in screw threaded engagement with the sleeve H² abutting at one end on the

2
collar H⁴ rigid on the shaft and at the other end on the pinion H⁵ rigid on the shaft.

H⁶ is a latch lever rigidly mounted on the nut H³ and having at its lower end the 5 latch jaw H⁷.

H⁸ is a manually controlled handle suspended at its upper end on and free to swing about the shaft H¹. The handle H⁸ is slotted as at H⁹, and contains the carriage H¹⁰ 15 slidably mounted therein and held in position by a plate H¹¹.

H¹² is a spring in the handle H⁸ adapted to yieldingly force the carriage H¹⁰ upwardly and to thrust the latch member H¹³ 15 normally into engagement with the latch jaw H⁷ as indicated in Fig. 3.

I is a pin rotatably mounted in the upper end of the carriage H¹⁰ and projecting on either side outwardly beyond the handle H⁸.

20 I¹ is a pentagonal head on the pin I.

I² is a flat spring on the handle H⁸ adapted to engage one flat side of the pentagonal head.

It will be noted that the pin I is rotatable 25 in the carriage H¹⁰ but carries keyed to its other end the five-pointed star or lever wheel I³. Each point or arm of the lever wheel terminates in two curved lugs I⁴, I⁵, of substantially the same contour as the 30 spaces between the teeth in the pinion H⁵.

I⁶, I⁷, are slots respectively on the side of the handle H⁸ and the plate H¹¹ to permit the sliding movement of the carriage H¹⁰ as it carries with it the pin I to be 35 resisted.

I⁸, I⁹, are springs projecting rearwardly 40 from the bearing bracket C on either side of the handle H⁸ and extending into and beyond the plane of the star wheel. In the 45 position shown in Fig. 3 with the handle to the right, the spring I⁹ yieldingly engages one of the arms and tends to rotate it in a clockwise direction. This yielding movement is resisted by the hook K which engages the next arm but one and prevents it 50 being thrust into engagement with the gear by the spring action of the member I⁹. The hook K¹ performs a similar function when the handle is in the left hand position, and 55 it prevents rotation of the star wheel in a counter clockwise direction. The hooks K, K¹, it will be noted, are spring hooks, and offer no resistance to the movement of the star wheel toward them but normally prevent a movement away. Mounted and 60 projecting rearwardly from the handle H⁸ is a bracket K² which carries the hooks K, K¹, and magnets K³, K⁴, having poles K⁵, K⁶ which extend down toward the hooks K, K¹, 65 which hooks serve as armatures for these poles, and when one or other of the magnets and poles are excited, the armatures or hooks are drawn toward the pole to release the arm.

Referring to the wiring diagram on Fig. 65 6, M is a conductor leading from any source

of electric power not shown to the crosshead B³. M¹ is a terminal brush on the right-hand end of the crosshead. M² is a terminal brush on the bracket B. M³ is a conductor leading from the brush M² to the magnet K³. 70 M⁴ is a conductor leading from the magnet K³ to the other terminal of the source of electric power. M⁵ is a brush on the left-hand end of the crosshead B³. M⁶ is a brush on the bracket B¹. M⁷ is a conductor 75 leading therefrom to the magnet K⁴, and M⁸ is a conductor leading from the magnet to the conductor M⁴.

O, O¹ are conductors leading from a suitable source of electric power to the motor E². 80

O², O³ are shunt conductors leading from the conductors, O, O¹ through a shunt coil O⁴. In this shunt coil is located an armature O⁵ withheld by a spring O⁶.

O⁷ is a switch blade actuated by the armature O⁵ attached when the armature O⁵ is drawn in owing to too great resistance in the motor, which in the usual way would build up a counter E. M. F. and shunt the current through the coil O⁴ to connect the 85 three switch points O⁸, O⁹, O¹⁰. O¹¹, O¹², O¹³ are conductors leading from these points or blades respectively to the conductors M, M⁷, and M³.

P is an arm projecting upwardly from the 90 part H⁶ and free to rotate with it.

P¹, P², are substantially semi-circular spring members attached at one end each to the arm P on opposed sides thereof, and at the other end each to the lower side of the 100 sleeve H². They tend, of course, normally to force the arm P into the position shown in dotted line in Fig. 3, so that the two springs form a substantially accurate circle.

The use and operation of my invention 105 are as follows:—The rivets are driven in the usual manner by the reciprocating dolly bar which carries one rivet head die and as it reciprocates compresses the rivet between such die and the fixed die on the 110 lower arm. The reciprocation on the dolly bar by the toggle action of the linkage is in the ordinary manner in response to the rotation of the main tension links about their pivotal point. This rotation is of course 115 caused by a reciprocation of the crosshead which, as it approaches the front end of the machine, rotates the links and causes them to exert the toggle effect.

Referring particularly to Fig. 2, it will 120 be noted that the crosshead is also a nut, and has in screw-threaded engagement therewith one end of a rotatable shaft. This shaft is normally when in the inoperative position as shown in Fig. 2, inclosed partially by the mechanism and partially by the sleeve projecting from the crosshead or nut. When it is desired to drive a rivet, the operator will move the control handle 125 from the central position toward the left, 130

thus rotating the nut and forcing the control shaft inwardly. This control shaft carries with it the male portion of the larger cone clutch, and as this cone clutch engages 5 with the rapidly moving female portion, which of course being driven by the electric motor is rotating at all times, the shaft will commence to rotate and feed the cross-head forward to operate the linkage and 10 drive the rivet. When the rivet has been driven, the operator will throw the handle back in the opposite direction rotating the nut in the opposite direction to withdraw the control rod and bring the small clutch 15 into operation. This will previously of course free the large clutch and cause the shaft to rotate in the opposite direction because the smaller clutch is rotating in the opposite direction. This will withdraw the 20 crosshead and move the dolly bar and rivet head die away from the work. Since less power is required, the gear ratio is of course smaller and the withdrawal of the cross-head is more rapid than its working movement. 25 Thus the machine can be completely controlled by the hand of the operator working on the control lever.

The operation of the automatic control and electric protective features of my device are as follows:—If the crosshead reaches the true limit of its excursion without having been stopped by the act of the 30 operator, the brush on the crosshead, which brush is preferably grounded though it need not be, will close the circuit through the terminal on the right hand bracket on the magnet, and the source of electric power, one terminal of which is grounded, to draw up the hook armature which holds the lever 35 wheel, and allow a finger to be thrown by the spring into engagement with the pinion on the end of the shaft. As the shaft is rotating in a counter clockwise direction, this will tend to force the finger toward the 40 handle, compress the spiral spring and release the latch lever and latch jaw carried thereby from the slidable latch when the spring is overcome and the slidable latch disengaged. The semi-circular springs will 45 then throw the control lever into the central position rotating the nut to draw the control shaft out to disconnect the clutch and allow the parts to remain at rest. The rivet driving screw in engagement with the nut 50 makes a self-locking mechanism and the nut therefore stays where it is put so that when the screw is rotated to force the nut or crosshead along to drive the rivet, the pressure on the rivet can be indefinitely 55

maintained merely by disconnecting the driving mechanism, and this pressure will not be released no matter how long the delay until the withdrawing connection is operated to withdraw the crosshead and positively release the rivet. 60

65

I claim:

1. In an electric riveting machine a slidably mounted screw-threaded crosshead, a drive screw in engagement therewith, a plurality of electrically driven drive members 70 constantly rotating about the screw in opposite directions, and at different velocities, clutch members mounted on and held against rotation with respect to the screw in opposition to said drive members and 75 means for throwing one of said clutch members at a time into engagement with its adjacent drive member to rotate the drive screw.

2. In an electric riveting machine a slidably mounted screw-threaded crosshead, a drive screw in engagement therewith, a plurality of electrically driven drive members 80 constantly rotating about the screw in opposite directions, clutch members mounted on 85 and held against rotation with respect to the screw in opposition to said drive members and means for throwing one of said clutch members at a time into engagement with its adjacent drive member to rotate the 90 drive screw.

3. In an electric riveting machine a slidably mounted screw-threaded crosshead, a drive screw in engagement therewith, a plurality of electrically driven drive members 95 constantly rotating about the screw in opposite directions, and at different velocities, clutch members mounted on and held against rotation with respect to the screw in opposition to said drive members and means 100 for throwing one of said clutch members at a time into engagement with its adjacent drive member to rotate the drive screw, said means comprising a control shaft within the screw and a connection from it to 105 each clutch member and means independent of the rotation of the screw and drive members for moving said shaft and clutch members in unison toward and from the appropriate drive member. 110

In testimony whereof, I affix my signature in the presence of two witnesses this 23rd day of November, 1914.

WENSEL MORAVA.
